MOP WRINGER

Dennis B. D. Blake, Denver, Colo., assignor of
one-half to Donald E. Willard, Danville, Ill.

Application November 19, 1934, Serial No. 753,598

6 Claims. (Cl. 15—262)

My invention relates to wringers for squeezing water from mops and is concerned more particularly with providing a device of this nature for domestic service.

One object of my invention is to devise a mop wringer in which the squeezing mechanism is foot operated and is mounted on a bucket-like container that is adapted to rest on the floor, thereby eliminating any necessity for stooping during the wringing operation.

A further object is to provide a wringer in which one of the cooperating squeezing rolls is yieldingly mounted to permit the application of a more or less constant squeezing pressure while the mop is being drawn between the rolls.

A further object is the provision of a wringer having squeezing rolls which are adapted to be separated a distance approximately equal to one dimension of the bucket to facilitate the positioning of the mop for squeezing.

A further object is to devise a wringer in which guide members are provided for definitely insuring the locating of the mop strands between the ends of the rolls, thus preventing any possibility of the strands becoming entangled in the axles of the rolls.

A further object is to provide in a wringer of the type described means for preventing tipping of the bucket during the squeezing operation.

These and further objects of my invention will be set forth in the following specification, reference being had to the accompanying drawings, and the novel means by which said objects are effectuated will be definitely pointed out in the claims.

In the drawings:

Figure 1 is a plan view of my improved mop wringer showing the squeezing rolls in spaced relation to receive a mop therebetween.

Fig. 2 is a section along the line 2—2 in Fig. 1, looking in the direction of the arrows.

Fig. 3 is a view similar to Fig. 2, but showing the squeezing rolls in the act of expressing water from a mop placed therebetween.

Fig. 4 is an elevation, partly in section, of a portion of the device, as viewed in the direction of the arrow 4 in Fig. 1, showing the means for returning the treadle to the position indicated in Fig. 2, following its release upon the completion of the squeezing operation.

Referring to Figs. 1 and 2 of the drawings, the numeral 10 designates a bucket for holding the liquid in which the mop is dipped. This bucket may have any desired conformation, but is preferably constructed with four flat walls, such as

the front wall 11, the rear wall 12, and the side walls 13.

A shelf 14 is secured to each side wall 13 adjacent the upper edge thereof and its junction with the front wall 11. A stationary squeezing roll 15 is rotatably mounted on the shelves 14 and extends substantially across the width of the bucket. Each of the shelves extends inwardly beyond the associated outer end of the roll 15 and its inner edge may be shaped as at 16 in order to guide the mop strands into contact with the surface of the roll 15 and definitely prevent any of the strands from becoming entangled with the axle of the indicated roll.

Within the bucket, a plate 17 is secured to the inner face of each side wall 13 and this plate is preferably formed with an elongated shape and symmetrically disposed with reference to the vertical center line of the associated side wall for a purpose hereinafter explained. A rock arm 18 is pivotally mounted as at 19 on each plate 17 and each arm is provided with a ledge 20 against which bears one end of a plunger 21 that is slidably mounted in a sleeve 22 which is also pivoted on the associated rock arm 18. One end of the sleeve 22 is closed by an adjustable plug 23 (see Fig. 3) and between this plug and the adjacent end of the plunger 21 is located a coil spring 24 which always causes the plunger 21 to bear against the ledge 20 and normally maintain the sleeve in the position shown in the drawings.

Each sleeve 22 is provided with an extension 25 and between these extensions is bridged a second squeezing roll 26 which is appropriately rotatably mounted upon a suitable axle extending between the indicated extensions. In order to facilitate the squeezing action, the roll 26 may have its squeezing surface curved as indicated in Fig. 1.

One end of a link 27 is pivotally connected to 40 the arm 18 and the opposite end is pivotally connected to a rock arm 28 which is fixed to a pin 29 that is rotatably mounted in the plate 17 and extends outwardly through the wall 13, it being understood that the construction just referred to is arranged on both of the side walls 13.

Arms 30 are secured on the outer ends of the pins 29, respectively, and extend forwardly of the front wall 11 for securing to a cross bar 31 to form a foot treadle 32. Preferably, a foot rest 33 is secured to the intermediate portion of the treadle 32 and may have its upper edge roughened to prevent slippage of the foot.

Referring to Fig. 4, and also to Fig. 1, it will be noted that these arms 30 are spaced some-

what from the adjacent side walls to permit the mounting of a coil spring 34 around the exposed portions of the pins 29. One end 35 of each of these springs is looped under the adjacent arm 30, while the opposite end 36 is received within a suitable pocket 37 provided on a plate 38 which is externally secured to the adjacent side wall 13. The usual bail 39 for carrying the bucket 10 is secured to the plates 38. For a purpose presently explained, a foot piece 40 is located forwardly of the front wall 11 and is connected to the bucket by an appropriate frame 41.

Figs. 1 and 2 illustrate the disposition of the squeezing mechanism when in retracted or non-operative position. Under these conditions it will be particularly noted that the squeezing rolls are fully spaced apart to a distance that approximates one dimension of the bucket, thereby providing free access to the interior of the bucket, such as for the dipping of the mop.

When it is desired to squeeze the mop, it is simply necessary to insert the mop in the bucket with the portion of the mop adjacent the handle thereof contacting the stationary roll 15. The operator then presses downwardly on the treadle 32 to thereby swing the roll 26 to the position shown in Fig. 3, whereupon the mop is drawn upwardly between the rolls and the pressure created through the treadle serves to express the water from the mop. During this operation, it will be particularly noted that it is possible to exert a substantially constant pressure against the mop, because of the yieldable mounting of the squeezing roll 26. This construction obviates any necessity for relieving pressure on the treadle in the event that extensive bulges or hard formations are encountered in the mop while the latter is being drawn upwardly. Moreover, due to the fact that each of the sleeves 22 is offset from the associated pivot 19 toward the rear wall 12 and forms with the attached extension 25 the limbs of the letter V, it is possible to retain the axis of the roll 26 within the confines of the bucket during its movement to and from squeezing position and to also insure that the sleeves will be well spaced from the mop strands during squeezing to prevent interference. The foregoing disposition also enables the roll 26 to be retracted the maximum distance as permitted by the dimensions of the bucket. The shelf 14 serves to definitely guide the mop strands into the proper position for being squeezed, while the foot 40 prevents any tendency of the bucket 55 to tip during the squeezing operation.

I claim:

1. A mop wringer comprising in combination, a bucket, a stationary squeezing roll, a pair of rock arms secured to opposite sides of the bucket, each arm having a ledge, a sleeve closed at one end and open at the opposite end pivotally carried by each of the arms, the open end being located adjacent the ledge, a plunger slidable in each sleeve with one end thereof projecting through the open end of the sleeve to bear against the ledge on the associated arm, a spring in each sleeve between the closed end thereof and the end of the associated plunger, a second squeezing roll bridged between extensions provided on the sleeves, a treadle pivoted on the bucket, and connections between the treadle and rock arms whereby the second roll is moved into squeezing relation with the stationary roll when the treadle is depressed.

2. A mop wringer comprising in combination,

a bucket, a stationary squeezing roll, a pair of rock arms pivotally mounted on the inner faces of a pair of the opposite sides of the bucket, extensions provided on the rock arms, a second squeezing roll bridged between the extensions, a treadle pivoted on the bucket and located externally thereof, the treadle pivots being mounted in said opposite sides and projecting into the interior of the bucket, an arm fixed to the inner end of each treadle pivot, and links connecting the arms and rock arms within the bucket whereby the second roll is moved into squeezing relation with the stationary roll when the treadle is depressed.

3. A mop wringer comprising in combination, a bucket, a stationary squeezing roll adjacent the front side of the bucket, a pair of rock arms secured to opposite sides of the bucket, each arm having a ledge, a sleeve closed at one end and open at the opposite end pivotally carried by each of the arms, the open end being located adjacent the ledge, a plunger slidable in each sleeve with one end thereof projecting through the open end of the sleeve to bear against the ledge on the associated arm, a spring in each sleeve between the closed end thereof and the end of the associated plunger, a second squeezing roll bridged between extensions provided on the sleeves, a treadle pivoted on the bucket, and connections between the treadle and rock arms whereby the second roll is moved into squeezing relation to the stationary roll when the treadle is depressed, each sleeve being offset rearwardly from the pivot of the associated rock arm and substantially forming the letter V with the attached extension whereby the sleeves are spaced from the mop strands during squeezing to prevent interference.

4. A mop wringer comprising in combination, a bucket, a stationary squeezing roll adjacent the front side of the bucket, a pair of rock arms pivotally mounted on a pair of the opposite sides of the bucket, a substantially V-shaped extension having first and second legs provided on each of the rock arms, the first leg of each extension being joined at one end to the associated rock arm at a point offset rearwardly from the pivot thereof and the other end of the first leg being connected to the second leg to form the vertex of the extension, a second squeezing roll bridged between the free ends of the second legs, said vertex lying adjacent the rear side of the bucket when the second roll is in retracted position, a treadle pivoted on said opposite sides of the bucket, the pivots of the treadle and rock arms being spaced from each other and located on opposite sides of the vertical center line of the bucket, respectively, and connections between the treadle and rock arms whereby the second roll is moved into squeezing relation to the stationary roll when the treadle is depressed, the rearward offsetting of the extension legs spacing the first leg from the mop strands during squeezing to prevent interference.

5. A mop wringer comprising in combination, a bucket, a stationary squeezing roll adjacent the front side of the bucket, a pair of rock arms secured to opposite sides of the bucket, each arm having a ledge, a sleeve closed at one end and open at the opposite end pivotally carried by each of the arms, the open end being located adjacent the ledge, a plunger slidable in each sleeve with one end thereof projecting through the open end of the sleeve to bear against the ledge on the associated arm, a spring in each sleeve

between the closed end thereof and the end of the associated plunger, a second squeezing roll bridged between extensions provided on the sleeves, a treadle pivoted on the bucket, and connections between the treadle and rock arms whereby the second roll is moved into squeezing relation to the stationary roll when the treadle is depressed, each sleeve being offset rearwardly from the pivot of the associated rock arm and substantially forming the letter V with the attached extension, and the distance between the centers of the second roll and rock arms being less than the distance of each arm center from the top edge of the bucket whereby the second roll substantially remains within the confines of the bucket during all movements.

6. A mop wringer comprising in combination, a bucket, a stationary squeezing roll adjacent the front side of the bucket, a pair of rock arms pivotally mounted on a pair of the opposite sides of the bucket, a substantially V-shaped extension having first and second legs provided on each of the rock arms, the first leg of each extension being joined

at one end to the associated rock arm at a point offset rearwardly from the pivot thereof and the other end of the first leg being connected to the second leg to form the vertex of the extension, a second squeezing roll bridged between the free ends of the second legs, said vertex lying adjacent the rear side of the bucket when the second roll is in retracted position, a treadle pivoted on said opposite sides of the bucket, the pivots of the treadle and rock arms being spaced from each other and located on opposite sides of the vertical center line of the bucket respectively, and connections between the treadle and rock arms whereby the second roll is moved into squeezing relation to the stationary roll when the treadle is depressed, and the distance between the centers of each rock arm and the second roll being less than the distance of each rock arm center from the top edge of the bucket whereby the second roll substantially remains within the confines of the bucket during all movements.
